Primary Examiner—T. Chase Nelson*Assistant Examiner*—Kathleen M Sims(74) *Attorney, Agent, or Firm*—Morgan Lewis & Bockius LLP(57) **CLAIM**

The ornamental design for a laundry countertop, as shown and described.

DESCRIPTION

FIG. 1 is a top, front, perspective view of a laundry countertop showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a reference view thereof.

The broken lines depict environmental structure that forms no part of the claimed design.
